No. 739,654.

PATENTED SEPT. 22, 1903.

G. B. DAVISON.
LIFTING JACK.
APPLICATION FILED OCT. 11, 1902.

NO MODEL.

UNITED STATES PATENT OFFICE.

GEORGE BENNETT DAVISON, OF UTICA, NEW YORK.

LIFTING-JACK.

SPECIFICATION forming part of Letters Patent No. 739,654, dated September 22, 1903.

Application filed October 11, 1902. Serial No. 126,854. (No model.)

To all whom it may concern:

Be it known that I, GEORGE BENNETT DAVISON, of Utica, in the county of Oneida, in the State of New York, have invented new and useful Improvements in Lifting-Jacks, of which the following, taken in connection with the accompanying drawings, is a full, clear, and exact description.

This invention relates to improvements in lifting-jacks, and refers more particularly to that class in which a hand-lever and gravity-pawls are employed to control the operation of a suitable plunger, hereinafter described.

I have sought in this invention to produce a light, strong, and durable wagon-jack which may be readily carried in the hand from place to place and which is free from bolts or rivets and capable of being readily assembled or disassembled with a minimum amount of labor and time.

To this end the invention consists in the combination, construction, and arrangement of the component parts of a lifting-jack, hereinafter fully described, and pointed out in the claims.

Referring to the drawings, Figure 1 is a top plan of a lifting-jack embodying my invention. Fig. 2 is a side elevation, partly broken away, of the parts seen in Fig. 1. Fig. 3 is a transverse section taken on line 3-3 of Fig. 2. Figs. 4, 5, and 6 are perspective views showing, respectively, the lifting and holding pawls and the link employed for transmitting motion from the operating-lever to the lifting-pawl.

Similar reference characters indicate corresponding parts in all the views.

In carrying out the objects of my invention I employ a hollow upright standard 1, which is mounted upon suitable supporting-legs 2, flaring outwardly and downwardly from the base of the hollow standard 1 and united at their lower ends to a substantially flat base-plate 3, adapted to rest upon the ground or other convenient support, the hollow standard 1 being supported a considerable distance above the base-plate and is provided with a lengthwise guide-opening 4 for receiving a reciprocally-movable lifting-plunger 5. The upper and lower ends of the guide-opening 4 are open, and the plunger 5 is movable through said open ends, the guide-open-

ing being of sufficient length to afford ample bearing for the plunger 5, and the central portion of the plunger is preferably reduced in thickness, so as to form opposite lengthwise bearing faces or ribs 6 at opposite longitudinal edges of the plunger. This plunger is of substantially the same cross-sectional form throughout its entire length, except that the upper end is slightly enlarged for forming a head 7, having a substantially flat bearing-face 8. The head 7 and body of the plunger 5 are formed integral with each other, and the hollow standard 1, legs 2, and base 3 are also cast together, the upper end of the upright standard 1 being formed with an upwardly-projecting lug or ear 9, having a slot or opening 10, in which is movable a suitable gravity-pawl 11, the lug 9 being located at one side of the plunger, and the lower edge of the slot or opening 10 serves as a fulcrum upon which the gravity-pawl 11 may be tilted for releasing the plunger in a manner hereinafter described.

The opposite outer faces of the upright standard 1 are formed with lugs 12, which are cast integral with the standard and form pivotal bearings for an operating-lever 13, the lugs 12 being disposed in proximity to the upper end of the standard 1, and the lever, being pivotally mounted upon said lugs, is also arranged in proximity to the upper end of the standard and is adapted to rock vertically. This lever 13 preferably consists of a metallic head of malleable iron or similar material, having one end bifurcated to receive the upper end of the standard 1, thereby forming oppositely-arranged arms 14, having their intermediate portions provided with apertures 15 for receiving the lugs or bearings 12, said arms extending transversely beyond the upright standard and are provided with additional apertures 16, in which is journaled a suitable link 17 for operating a lifting-pawl 18.

The opposite end of the metallic head of the operating-lever 13 terminates in a hollow boss 19 for receiving a handle 20, said handle fitting in the socket of the hollow boss 19 and is readily removable therefrom during transportation in order to economize in space and facilitate the packing of the jacks in large quantities for storage or shipment.

The holding and lifting pawls 11 and 18 are preferably formed of cheap cast metal, such as malleable iron, and are provided with openings 21 and 22 for receiving the plunger 5. These pawls are located between the upper end of the standard 1 and head 7 of the plunger 5, the holding-pawl 11 being located beneath the lifting-pawl 18 and is provided with a finger-piece 23, cast integral therewith 10 and extending outwardly and upwardly from the lug or ear 9, whereby the operator may readily engage the portion 23 and rock the rear end of the pawl upwardly upon the fulcrum previously mentioned for releasing the same from engagement with the front and rear faces of the lifting-plunger 5. As previously stated, these pawls are formed from malleable iron or similar metal, and are therefore too soft to stand the wear incidental to 20 the frictional engagement of the opposite ends of their respective openings with the front and rear faces of the lifting-plunger 5. I therefore provide each of the pawls 11 and 18 with a pair of nibs or biting-teeth 24, 25 which consist of hardened pins of different material from the pawls, such as hardened steel, which are inserted through the walls of the openings in such manner as to form the front and rear engaging faces of the openings 30 in the pawls, which faces bite upon the opposite edges of the lifting-plunger as the lever is operated, the lifting-pawl serving to elevate the plunger at each downward movement of the handle of the lever 13, and the pawl 11 operates to hold the plunger in its adjusted position.

The lifting-pawl 18 projects beyond the rear edge of the plunger and is provided with an additional opening 25 and suitable bearings 40 26 for receiving the upper end of the link 17. This link 17 is formed at its lower end with pintles 26', cast integral therewith and inserted into the openings 16, the upper end of said link being provided with bearings 27, 45 normally seated in the bearings 26, and is also provided with a hook-shaped extremity 28, projecting through and above the opening 25 and adapted to engage the rear wall of said opening to effect the positive operation of the pawl 18 and also to prevent its accidental displacement from engagement with the link 17.

The end walls of the openings 21 and 22 in the pawls 11 and 18 are preferably V-shaped, with their apexes in close proximity to the 55 opposite edges of the lifting-plunger, and the nibs or pins 24 are inserted through the apexes of these end walls, so as to project inwardly slightly beyond these apexes, so as to insure their engagement with the front and rear 60 edges of the lifting-plunger.

It is apparent from the foregoing description that the pawls 11 and 18 are fulcrumed respectively upon the lug 9, bearings 27 at opposite sides of the lifting-plunger, and that 65 their ends, which engage the lifting-plunger, are free to drop by gravity, and therefore tend to impinge their nibs against the opposite

faces of the lifting-plunger, this tendency in the lifting-pawl serving to lift the plunger when the handle 20 is depressed, and the nibs 70 of the pawl 11 also bite upon the opposite edges of the plunger and prevent further downward movement thereof.

When it is desired to lower the lifting-plunger gradually, the operator simply engages the portion 23 and rocks the inner end of the pawl upwardly, and at the same time, having a firm grip upon the handle 20, permits the plunger to gradually descend.

In assembling the lever upon the studs 12 80 and pintles 26' the arms 14 are spread a sufficient distance to receive the studs and pintles for the purpose of alining the same with their respective apertures in the arms 12, whereupon said arms are drawn or forced toward 85 each other, and the parts are thus positively connected or assembled.

The holding-pawl 11 is provided with laterally-projecting lugs 30, depending from its lower face and projecting into the path of the 90 lever 13, so that when it is desired to lower the plunger instantly it is simply necessary to rock the lever until the upper faces of the arms 14 engage the lugs 30 and elevate the pawl, whereupon the lifting-plunger drops to 95 its lower limit.

Having thus fully described my invention, what I claim, and desire to secure by Letters Patent, is—

1. A lifting-jack comprising a hollow upright standard, a lifting-plunger guided on the standard, a lever fulcrumed on the upper end of the standard and extending to opposite sides thereof, a holding-pawl fulcrumed on the standard above and at one side of the lever-fulcrum, a link pivotally mounted on the lever at the other side of the fulcrum and rising therefrom, and a lifting-pawl fulcrumed on the upper end of the link above the holding-pawl and engaging the lifting-plunger for 100 the purpose described.

2. In a lifting-jack, the combination of an upright standard having a lengthwise opening, a lifting-plunger guided in said opening, a lever mounted on the standard and extending to opposite sides thereof and having a handle at one end, a link pivotally mounted on the other end of the lever and rising therefrom, a lifting-pawl fulcrumed on the upper end of the link above the lever, and the holding-pawl fulcrumed on the standard above the lever, said pawls being provided with nibs of different material than the pawls, for the purpose described, the holding-pawl being provided with a finger-piece extending on the 110 side of the fulcrum opposite to the nibs.

3. In a lifting-jack, the combination with an upright standard having depending legs and a flat base, said standard being provided with a lengthwise opening, a lifting-plunger guided in the opening, a lever pivotally mounted on the upper end of the standard, a link projecting upwardly from the lever, a gravity lifting-pawl mounted on the upper 130

end of the link above the lever, a gravity holding-pawl fulcrumed on the standard and interposed between the upper end of the standard and the lifting-pawl, and provided with a finger-piece, for the purpose set forth.

4. In a lifting-jack, the combination with an upright standard formed of cast metal and having bearings cast on its opposite faces, a lever having a bifurcated extremity, the arms of which are flexible and perforated to receive said bearings, a plunger guided on the standard, a link mounted between said arms, a lifting-pawl mounted on the link and pro-

vided with nibs for engaging opposite faces of the plunger, and a holding-pawl fulcrumed on the standard and provided with nibs also engaging the opposite faces of the plunger, this latter holding-pawl being also provided with lugs adapted to be engaged by the lever for tripping the holding-pawl.

In witness whereof I have hereunto set my hand on this 26th day of September, 1902.

GEORGE BENNETT DAVISON.
